DESIGN FOR A DOUGHNUT LIFTER

Clara A. Burge, Castlewood, S. Dak.

Application February 7, 1935, Serial No. 55,295

Term of patent 7 years

To all whom it may concern:

Be it known that I, Clara A. Burge, a citizen of the United States of America, residing at Castlewood, in the county of Hamlin and State of South Dakota, have invented a new, original, and ornamental Design for Doughnut Lifters, of which the following is a specification, reference being had to the accompanying drawing, forming part thereof.

I claim:—

The ornamental design for a doughnut lifter, as shown.

CLARA A. BURGE.
